[**] Term: **14 Years**

[57] **CLAIM**

[21] Appl. No.: **34,667**

The ornamental design for a free turning sleeve for a locking lug nut, as shown and described.

[22] Filed: **Feb. 9, 1995**

DESCRIPTION

[51] LOC (6) Cl. **08-08**

FIG. 1 is a side elevational view of a free turning sleeve for a locking lug nut showing my new design, the adjacent and opposite sides being identical in appearance;

[52] U.S. Cl. **D8/399**

FIG. 2 is a vertical cross-section view thereof, taken through the center of the sleeve;

[58] **Field of Search** D8/330, 331, 343, D8/346, 382, 383, 396, 397, 399; 70/232

FIG. 3 is an end elevational view thereof;

D. 311,131 10/1990 Saito D8/397

FIG. 4 is an opposite end elevational view thereof; and,

D. 329,103 9/1992 Stoner, Jr. ..... D8/396 X

FIG. 5 is an end perspective view thereof.

D. 366,826 2/1996 Heithaus D8/396

The broken-line disclosure in FIGS. 1 and 2 is for illustrative

3,605,460 9/1971 Singer 70/232

purposes only and forms no part of the claimed design.
